(57) **CLAIM**

We claim the ornamental design for a cooler cart, as shown and described.

DESCRIPTION

FIG. 1 is a perspective view of a cooler cart, showing our new design.

FIG. 2 is a front view thereof;

FIG. 3 is a back view thereof;

FIG. 4 is a top view thereof;

FIG. 5 is a bottom view thereof; and,

FIG. 6 is a left side view thereof, the right side view being a mirror image thereof.

The dash-dash broken lines shown in the drawings illustrate portions of the cooler cart that form no part of the claimed design.

1 Claim, 6 Drawing Sheets
